UNITED STATES PATENT OFFICE

MORRIS M. TITTERINGTON, OF BROOKLYN, NEW YORK, ASSIGNOR, BY MESNE ASSIGNMENTS, TO THE PROSPERITY COMPANY, INC., OF SYRACUSE, NEW YORK, A CORPORATION OF NEW YORK

GARMENT PRESS

Application filed June 9, 1924. Serial No. 718,681.

This invention relates to pressing machines and particularly to garment presses; and a main object of the invention is to produce an improved garment pressing machine of small compact size adapted to be hand or foot closed and which is adapted to apply final pressure by improved power means.

Another principle object of the invention is to produce a pressing machine having correspondingly equal sized pressing jaw members possessing a novel movement to provide extended visibility of the work and easy access thereto without at the same time raising the press head high off the buck, the object being to combine this feature with operating means, power driven if desired, all parts of which are located within the frame of the press to avoid the ordinary present day rearwardly extending horizontal and weighted press lever which usually requires considerable floor space to permit the old style lever to swing up and down to the rear of the press frame. To this end one of my improvements relates to a vertically disposed press lever, the movement of which does not extend beyond the boundary of the pressing machine frame, and my machine therefore requires no more space than the frame itself requires; and the novelty of this feature rests in part in the combination thereof with improved operating mechanism.

Another object of the invention is to produce an improved pedal and toggle of less number parts than ordinarily employed, and to use in connection therewith motor means for producing final pressure; and a feature of my invention is the combination of a diaphragm with a lever to impose high pressure between the press jaws.

My invention further relates to improvements over the pressing machine invention described in my application Serial Number 687,765, filed January 22, 1924.

The accompanying drawings illustrate a preferred embodiment of the invention and it is understood how changes in construction and mode of operation may be made without departing from the scope and principle of the invention.

Figure 1 shows a side view of the pressing

machine with the press head open. The dotted outline indicates closed position of the press jaws but with the pedal 30 omitted in dotted lines, and the motor means, being the improved diaphragm pressure developing element, is shown at rest just prior to expansion to apply final pressure to the press jaws. This view also illustrates a toggle and pedal element of composite structure which is characterized in that an extension of one of the toggle links forms the pedal.

Figure 2 shows a side view of the lower portion of the press with the motor means and toggle in high pressure position with the pedal 30 also omitted for clearness.

Figure 3 shows a cross sectional view as developed along the line 3-3 of Figure 2, and the pedal 30 is left off in this view as well.

Referring further to the drawings for a detailed description of the invention, there is shown a pressing machine frame 10 having the usual table 11 and back plate 12 to prevent the garment from falling off of the table to the rear; and a legged type frame is shown but it is to be understood that a pedestal frame may be employed if desired. The frame supports a press buck 13, and both pressing jaws, the buck 13 and head 15, may be heated by suitable means such as steam or electricity. The heating means, however, is not illustrated because my invention particularly relates to an improved construction in press operating mechanism intended to reduce the size of pressing machines in general and simplify their construction.

The pressing head 15 is carried on the upper end of a vertically disposed press lever composed of an upper yoke or arch 16 and a lower arm 17 integral therewith. The lever is pivoted at 18 on the press frame 10 and hooks over or curves around the plate 12 and reaches forwardly to carry the press head 15 back and forth up and down on the buck; and the novel mode of action possessed by the press lever causes the head 15 to undergo a compound rearwardly and upwardly sweeping motion whereby the front edge of the press head 15 sweeps backwardly from the front edge of the buck 13 as well as rising thereabove, thereby exposing the pressing

surface of the buck to extended visibility to provide an unobstructed view of the work. Furthermore in my pressing machine it is not necessary to lift the head 15 so high as with the usual style of pressing machines for the reason that the said head is moved rearwardly, while in present day pressing machines the head must necessarily undergo long movement to gain visibility and access to the work which leads into complicated operating mechanism for performing such high head lift. Instead of operating my press jaws by simple angular movement, which after all still leaves the large size press head poised directly over the buck, I combine rectilinear motion therewith which imparts to the head a rearward throwback action simultaneously with the angular rising movement; and to accomplish the results named it is noted that the lever fulcrum point 18 is placed below the meeting or pressing jaw plane and to the rear of the longitudinal axis of the pressing jaws. In carrying out the foregoing mode of operation I am enabled to remove the usual rearwardly projecting lever arm with exposed counterbalance weight and install it inside the press frame together with a new toggle pedal locking means, the separate elements of which do not wholly constitute my invention, for that more particularly is in the combination.

The lower arm 17 of the press lever projects downwardly in a substantially vertical direction and is adapted to swing in and out of the frame as shown in the two positions in Figure 1. An improved feature of my invention is the compact design of the operating mechanism whereby the press lever 17 is caused to remain within the bounds of the frame and not permitted to swing beyond the limits thereof for the reason that to do so would take up space and be wasteful of floor area such as now is so common of pressing machines on the market. My machine is intended to be operated by hand or by pedal for closing the head thereof, and immediately after the pressing members have made contact, the power means is manually turned on or automatically turned on, as the case may be, for the purpose of applying final pressure by power means to save unnecessary labor on the part of the operator. Preferably the head of the press is closed by hand, and for this purpose a handle 19 is provided on the head by which the operator pulls the head forwardly and downwardly, but it will be shown how a foot pedal may be used in this connection as well.

A counterbalance weight acts against the press lever to equalize the weight of the head 15, and to this end a bell crank 21 is pivoted at 22 on the frame and on one arm thereof a weight 23 is fixed while the other arm thereof is pivotally connected by a link 24 to the press lever 17. The weight and applied leverage of the counterbalance member 23 acts to poised

the head 15 in such a manner that an operator may readily pull the head downwardly and forwardly by hand in contact with the buck 13, but the weight 23 may if desired overbalance the head to automatically open the press at the end of the pressing period.

A toggle locking and pedal closing mechanism consists of a link 26 pivotally connected to the press lever at 27 and pivotally connected at 29 to a companion link 28; and the link 28 has the other end thereof pivotally mounted upon a power lever as will be described. A removable pedal 30 has the inner end 31 bolted onto the link 26 and reaches around the link 28 and projects forwardly of the frame where it is in convenient position for the operator to place his foot thereon to facilitate the straightening of the toggle 26-28. The pedal 30 may of course be integrally formed with the link 26, but in the present disclosure I have illustrated it as being detachable from the toggle link 26 for the purpose of removing the pedal entirely from the pressing machine thereby permitting the press to be closed by hand power only. The pedal 30 is only shown in up position, the press being open, and is omitted from other views for clearness.

A bell crank having lever arms 32 and 33 is pivoted at 34 to the frame 10. The arm 32 is made considerably longer than the depending arm 33 for the purpose of producing leverage. The lower end of the short arm 33 pivotally supports the lower end of the short toggle link 28, and the bell crank 33 therefore acts as a support for one end of the toggle 26-28. A pivot pin 35 pivotally connects the toggle link 28 to the bell crank arm 33 and acts more or less as a fixed support against which the toggle 26-28 pushes or reacts in reaching the straightened position shown in dotted lines in Figure 1. A reach lug 36 is made integrally with one of the toggle links, as with link 28, and an adjustment screw 41 is carried thereby to bring the toggle to a stopped overstraightened position as shown in Figure 1 dotted line position; and the overstraightened position is accurately set by the screw.

The pivot pin 35 also carries a kick-off pedal comprising a foot piece 37 with a rear arm 38 carrying a lug 39 reaching underneath the pivot pin 29 connecting together the two toggle links 26 and 28. The kick-off pedal normally rests against a frame stop 40 and stands in position ready to thrust upwardly against the toggle to break its locked position to open the press. The operator is required to exert only slight pressure on the kick-off pedal 27 to break the toggle causing the head 15 to rise.

The long lever arm 32 of the power bell crank reaches rearwardly and is acted on by motor means for the purpose of producing final pressure; and in this instance I have

- produced an improvement in power presses, for rather than use an electric motor, or a steam or air cylinder, I employ an improved diaphragm or fluid pressure motor for moving the arm 32 through a short distance under great power to impart a short rearward thrust to the straightened and locked toggle 26-28 after the head is closed, to impose high compression between the pressing jaws. 5
- 10 A bellows or diaphragm cup or housing 42 is secured to the frame 10 by a bracket 43. The bellows or diaphragm 48 has its lower end anchored to a head 44. The head is provided with a locking lug 45 which rests in the housing 42, and a steam or air pipe connection 46 is established with the head 44 to supply steam or air to the motor means from a pipe 47. The diaphragm 48 has its upper end anchored between a concave head 15 49 and a screwed on cover plate 50. The part 50 may project over the rim of the housing 42 if desired to completely enclose and protect the bellows element 48. A post 51 is made integral with the bellows head 49-50 20 and reaches up to engage the end of the lever 32. The bellows unit 48 stretches out under fluid pressure admitted thereto to swing the longer arm 32 upwardly which correspondingly swings the short bell crank arm 33 rearwardly to produce a thrust through the over-straightened toggle linkage 26-28. 25
- The steam-pipe 47 is equipped with a valve 52 which is provided with an exhaust port 53. A valve control rod 54 connects with the 30 stem of the valve 52 and reaches forwardly of the frame where the front end of this rod is equipped with a double acting valve control member having opposite foot pieces 55 and 56. When the operator depresses the 35 pedal end 55, the fluid pressure is exhausted from the diaphragm 48 out through the exhaust port 53; and when the operator depresses the other end 56 of the foot pedal, steam or fluid pressure is quickly admitted 40 from the pipe 47 into the pipe connection 46 to expand the bellows and produce high pressure between the pressing jaws as explained. 45
- In the operation of the machine, the operator spreads the work upon the buck 13 and 50 draws the head closed by using the handle 19 or by depressing the pedal 30, or by using both such means if desired. By the time the head 15 reaches engagement with the work, the toggle 26-28 has reached straight line 55 position and has slightly overstraightened itself to produce a locked condition such that the said toggle 26-28 stands out in a slightly overstraightened condition under the strain and thrust imposed therethrough by the bell 60 crank arm 32 when the high pressure motor means acts.
- The operator next depresses the pedal 56 which oscillates the rod 54 to open the valve 52 thereby admitting fluid pressure under the 65 motor head 49 of the unit whereupon the diaphragm instantly expands upwardly to that position shown in Figure 2, the result of which is to impose extremely high pressure between the pressing jaws. After the pressing period has been prolonged a suitable time, 70 the operator depresses the other side or end 55 of the motor control pedal to cause the pressure to discharge from the unit 48 thereby permitting the bell crank arm 32 to gravitate downwardly which quickly and noiselessly 75 removes high pressure from the head, whereupon the operator depresses the kick-off pedal 37 which breaks the toggle 26-28 upwardly thereby permitting the head 15 to quickly rise as it is lifted by the counter weight 23. 80
- My improved motor means saves the expense of manufacturing the piston and cylinder elements necessarily employed in fluid pressure motors heretofore used. Furthermore its use eliminates the leakage of water 85 and oil which always occurs around the ordinary fluid pressure motor such as an engine or a pump. Very little expansion or movement is required of the motor 48 for the reason that the pressing jaws are brought into 90 close contacting engagement before the diaphragm acts. Final pressure is imposed by introducing a strain throughout the operating mechanism which is carried out without apparent motion of parts. The only appreciable moving operating parts is the short 95 upward stroke of the outer arm 32 and the bell crank which travels a very short distance due to the fact that the head 15 has already engaged the work and buck prior to 100 starting the motor means. Furthermore, my improved power press and its motor means is very economical in fluid pressure such as steam for the reason that the head 49 is concaved into the element 48 which fills up 105 the entire space ordinarily present in the bellows and thereby requiring a relatively small amount of fluid pressure to operate the motor means. 110
- What I claim is:
1. A pressing machine comprising cooperating press jaws including a head and buck, a frame, a press lever fulcrumed in the frame and carrying the head by which the jaws are opened, a corrugated diaphragm mounted on the frame, means for supplying fluid pressure to the diaphragm, a locking toggle connected with the press lever to hold the press jaws closed, a power lever fulcrumed on the frame having one end connected to the toggle 120 and the other end connected with the diaphragm, hand closing means for pulling the head down upon the buck, and a pedal extension made on and as a part of the toggle to facilitate the manual closing of the head. 125
  2. A pressing machine comprising cooperating press jaws including a head and buck, a frame, a press lever fulcrumed in the frame and carrying the head by which the jaws are opened, a corrugated diaphragm mounted on 130

the frame, means for supplying fluid pressure to the diaphragm, said press lever being disposed in a vertical position with the upper end curving forwardly to reach the head and its lower end projecting inside the frame, said lower end of the press lever being adapted to swing inside the frame to open wide the press, a counter balance member pivoted inside the frame and adapted to swing within the frame limits, a connection made between the press lever and counter balance member, a locking toggle connected with the press lever to hold the jaws together, a pedal forming one element of the toggle and adapted to help close the press, and a connection established between the diaphragm and locking toggle.

3. A pressing machine comprising cooperating press jaws including a head and buck, a frame, a press lever fulcrumed in the frame and carrying the head by which the jaws are opened, motor means for applying final pressure, said press lever being disposed in a vertical position with the upper end curving forwardly to reach the head and its lower end projecting inside the frame, said lower end of the press lever being adapted to swing inside the frame to open wide the press, a counter balance member pivoted inside the frame and adapted to swing within the frame limits, a connection made between the press lever and counter balance member, a locking toggle connected with the press lever to hold the jaws together, a pedal forming one element of the toggle and adapted to help close the press, and a connection established between the motor means and locking toggle.

4. A pressing machine comprising in combination, a frame, a head and buck, a press lever yoke pivoted on the frame and reaching over the buck and fixed to the head, said lever being pivotally carried on the frame at a point below the pressing plane of the meeting head and buck which imparts a compound upwardly and rearwardly swinging motion to the head carrying the front edge of the head up and back from the buck, a downwardly projecting press lever arm integral with the press lever and designed to move within the frame limits, connected links forming a locking toggle to hold the head down, one toggle end being pivoted to the lower end of the aforesaid arm to swing the head down when the toggle straightens and swing the head up when the toggle breaks, said toggle adapted to lock the head down, unlocking means arranged to break the toggle, another lever pivoted on the frame and to which is connected the other end of the toggle, and means for actuating the last named lever with great force to produce high compression in the press.

5. A pressing machine comprising in combination, a frame, a table carried thereon, a press buck carried on the frame, a movable

press head coacting with the buck, a press lever pivoted on the frame and disposed in a vertical position, a yoke made on the upper end of the press lever and reaching over the table and attached to the head, the press lever frame fulcrum point being located below the pressing plane and to the rear of the longitudinal axis of the head and buck to introduce a compound motion of the head to throw it back away from the front edge of the buck and simultaneously raise it above the buck to expose the buck to view, a counterbalance means connected with the press lever, a toggle connecting with the lever to hold the press head down, said toggle being disposed horizontally in the frame with one end of the toggle pivotally mounted on the front of the frame and the rear end of the toggle connected with the lower end of the press lever, and means for applying a thrust through the toggle to produce compression between the head and buck.

6. A pressing machine comprising in combination, a frame, a table carried thereon, a press buck carried on the frame, a movable press head coacting with the buck, a press lever pivoted on the frame and disposed in a vertical position, a yoke made on the upper end of the press lever and reaching over the table and attached to the head, the press lever frame fulcrum point being located below the pressing plane and to the rear of the longitudinal axis of the head and buck to introduce a compound motion of the head to throw it back away from the front edge of the buck and simultaneously raise it above the buck to expose the buck to view, a counterbalance means connected with the press lever, a locking means connecting with the lever to hold the press head down, a housing mounted in the frame, a corrugated power bellows therein contained with one end anchored to the housing and the other end left free to expand, means supplying fluid pressure to the fixed bellows end, and a connection established between the expansible bellows end and the aforesaid locking means to produce compression between the head and buck.

7. A pressing machine comprising in combination, a frame, a table carried thereon, a press buck carried on the frame, a movable press head coacting with the buck, a press lever pivoted on the frame and disposed in a vertical position, a yoke made on the upper end of the press lever and reaching over the table and attached to the head, the press lever frame fulcrum point being located below the pressing plane and to the rear of the longitudinal axis of the head and buck to introduce a compound motion of the head to throw it back away from the front edge of the buck and simultaneously raise it to expose the buck to view, a counterbalance means connected with the press lever, a toggle having its rear

- end connected with the lower end of the lever to hold the press head down, a power lever for applying pressure pivoted on the frame and connected with the front end of the toggle, a motor means connected with the power lever. 5
8. A press comprising in combination, a frame, cooperating press jaws, a vertical press lever adapted to open and close the jaws, a substantially horizontally mounted toggle having one end attached to the lower end of the vertical press lever, movable means carried by the frame supporting the other end of the toggle, and a toggle operating pedal including a foot piece carried on the toggle and projecting forwardly from the frame to straighten the toggle and close the jaws, and motor means to actuate the movable means to exert a thrust through the toggle and produce jaw compression. 10
9. A press comprising, a frame, a cooperating press buck and head, a vertical press lever including an upper arch reaching over the buck and attached to the head to open the press and including a downwardly extending arm, a frame pivot carrying the press lever to the rear and below the buck and head; press head balancing means including, a bell crank pivoted on the frame underneath the buck and head, a weight on one end of the bell crank, a link connecting the bell crank to the press lever; and mechanism to operate the press lever to open and close the press. 15
10. A press comprising, a frame, a cooperating press buck and head, a vertical press lever including an upper arch reaching over the buck and attached to the head to open the press and including a downwardly extending arm, a frame pivot carrying the press lever to the rear and below the buck and head; press head balancing means including, a bell crank pivoted on the frame underneath the buck and head, a weight on one end of the bell crank and swinging up and down toward the front of the press, a link connected with the press lever arm below the frame pivot; and operating means to open and close the press and including, a toggle one end of which is connected to the lower end of the press lever and means supporting the other end thereof on the press frame. 20
11. A press comprising, a frame, a cooperating press buck and head, a vertical press lever including an upper arch reaching over the buck and attached to the head to open the press and including a downwardly extending arm, a frame pivot, carrying the press lever, to the rear of and below the buck and head; and mechanism to operate the press lever to open and close the press including, operator actuated means to aid in closing the press, motor means, a toggle embodying pivotally connected links one of which is connected to the press lever arm, a bell crank pivoted on the frame and hav- 25
- ing two arms one of which connects with the motor means and the other of which connects with the other toggle link. 30
12. In a press, a frame and a head and buck carried thereby, an upright swingable press head actuating member arched around the buck and attached to the head, pivot means carried by the frame below the head and buck and on which the member is movably carried, a bell crank pivoted on the frame and toggle means connecting it with the lower end of the head actuating member to move the same on the pivot means, means to work the bell crank, and means mounted on the frame and connected to the member above the toggle to balance the member and the press head. 35
13. In a press, a frame and a head and buck carried thereby, an upright swingable press head actuating member arched around the buck and attached to the head, pivot means carried by the frame below the head and buck and on which the member is movably carried, a lever carried below the buck within the frame, toggle means having one end connected to the lever and the other end connected to the lower extremity of the member, means to work the lever, a pedal below the toggle means and connected therewith, and balancing means under the buck within the frame and connected with the member above the toggle to balance the head and member. 40
